UNITED STATES PATENT OFFICE.

MONROE S. CLAWSON, OF UPPER MONTCLAIR, NEW JERSEY.

REFRACTORY COVER FOR ELECTRIC FURNACES.

1,410,654.

Specification of Letters Patent. Patented Mar. 28, 1922.

Application filed December 1, 1920. Serial No. 427,546.

To all whom it may concern:

Be it known that I, MONROE S. CLAWSON, a citizen of the United States, residing at Upper Montclair, in the county of Essex and State of New Jersey, have invented new and useful Improvements in Refractory Covers for Electric Furnaces, of which the following is a specification.

This invention relates to electric furnaces and has for its object the provision of a sectional refractory cover adapted to enclose the crucible or "boat" whereby to retain the heat and to prevent oxidation to a greater or less extent, while the melting is progressing.

An important object is the provision of a device of this character which is so constructed that the sections of the cover may be readily separated without necessitating touching them, the device being consequently of distinct advantage in preventing exposure of the operator to excessive heat.

An additional object is the provision of a device of this character in which the sections of the cover will be automatically retained in contacting relation.

A further object is the provision of a device of this character which will be simple and inexpensive in construction, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a plan view of my complete apparatus showing the upper section of the cover removed, and

Figure 2 is a central longitudinal sectional view.

Referring more particularly to the drawings, I have shown a pair of frame members disposed in upright position and arranged in spaced parallel relation. At suitable intervals these frames are connected by rods or the like 11 which hold the frames in their proper relation. The upper portions of these frame members constitute tracks 12.

Secured upon the frames near one end thereof are upright brackets 13 which form supports for the furnace. The furnace comprises heads 14 between which is the crucible or "boat" 15. The heads are carried by shanks 16 threaded through the brackets

13 and provided with hand wheels 17 by means of which the heads may be brought into clamping engagement with the crucible. It is preferable that the heads be hollow and water cooled and for this purpose the heads are provided with pipes 18 and 19. The numeral 20 designates a handle connected with one or each of the heads whereby they may be rotated partially to tilt the crucible for pouring. Connected with the heads are suitable conductors 21 leading from a source of current illustrated conventionally at 22.

The crucible cover device comprises a carriage 23 mounted upon flanged wheels 24 traveling on the tracks 12. The carriage includes side members connected by a shaft or rod 25. The cover proper consists of mating members 26 and 27 formed of refractory material and adapted to enclose the crucible. These members 26 and 27 are carried by arms 28 and 29, respectively, which are pivoted in crossed relation upon the shaft 25 and which have their free ends provided with handles 30 and 31, respectively. The handle 30 is weighted or formed as a weight whereby to overbalance the lower cover section and cause it to engage against the bottom portion of the crucible. The handle 31 is lighter than the upper section of the cover so that the upper section will normally gravitationally engage the crucible.

In the use of the device, assuming that the cover sections 26 and 27 are initially separated by pressing the handles 30 and 31 apart, the carriage 23 is moved along the tracks until the cover sections are in position to be engaged with the crucible. The cover will then enclose the crucible and not only serve to retain the heat caused by passage of current therethrough but will also serve to prevent, to great extent, the oxidation of the metal being melted. When it is desired to remove the cover it is merely necessary that the operator move the handles 30 and 31 apart and then slide the carriage 23 along the tracks to bring the cover sections away from the crucible.

From the foregoing description and a study of the drawings it will be apparent that I have thus provided a very simply constructed cover device which will automatically be maintained normally in clamping position and which is readily removable from engagement with the crucible without any necessity for touching the cover

device owing to the provision of the tong-like arrangement.

While I have shown and described the preferred embodiment of my invention, it is of course to be understood that I reserve the right to make such changes in the form, construction, and arrangement of the parts as will not depart from the spirit of the invention or the scope of the subjoined claims.

10 Having thus described my invention, I claim:

1. In combination with an electric furnace including a crucible supported between heads, a cover of refractory material formed in sections adapted to be engaged upon the crucible whereby to enclose the latter and handles connected with the sections and pivoted in crossed relation.

2. In combination with an electric furnace including a crucible supported between heads, a cover of refractory material formed in sections adapted to be engaged upon the crucible whereby to enclose the latter, and a carriage from which the cover is supported, 25 the carriage being movable to bring the cover toward or away from the crucible.

3. In an electric furnace including heads and a crucible disposed therebetween, a carriage movable toward and away from the crucible, and a sectional cover for the crucible formed of refractory material and carried by said carriage.

4. In an electric furnace including elec-

trodes and a crucible disposed therebetween, a refractory cover for the crucible comprising a pair of mating sections, and pivoted arms carrying said sections. 35

5. In an electric furnace including electrodes and a crucible disposed therebetween, a refractory cover for the crucible comprising a pair of mating sections, and pivoted arms carrying said sections, said arms being arranged in crossed relation and having their free ends provided with handles. 40

6. In an electric furnace including electrodes and a crucible disposed therebetween, a refractory cover for the crucible comprising a pair of mating sections, and pivoted arms carrying said sections, said arms being arranged in crossed relation and having their free ends provided with handles, the handle on the arm carrying the lower section being heavier than the lower section and the handle on the arm of the upper section being lighter than the upper section 50 whereby said sections will normally engage the crucible. 55

7. In combination with an electric furnace including a crucible supported between heads, a carriage movable toward and away from the crucible, and a cover for the crucible formed of refractory material and supported by the carriage. 60

In testimony whereof I hereto affix my signature.

MONROE S. CLAWSON.
